UNITED STATES PATENT OFFICE.

EDWARD W. ANDEREGG, OF ALGOMA, WISCONSIN.

MACHINE FOR APPLYING METAL TIPS TO CORD.

1,087,420.

Specification of Letters Patent. Patented Feb. 17, 1914.

Application filed March 8, 1913. Serial No. 753,057.

To all whom it may concern:

Be it known that I, EDWARD W. ANDEREGG, citizen of the United States, residing at Algoma, in the county of Kewaunee and State of Wisconsin, have invented certain new and useful Improvements in Machines for Applying Metal Tips to Cord, of which the following is a specification, reference being had to the accompanying drawings.

This invention relates to a machine for applying metal tips to the ends of cord lengths such as are employed in the manufacture of fly nets, the invention having for its primary object to provide, simple, efficient and positively operating mechanism whereby the metal tips are easily, quickly and securely applied to the ends of the cords to prevent the strands thereof from unraveling.

Another object of the invention is to provide an improved form of knife whereby the metal bands from which the tips are formed and the cord are simultaneously cut or severed.

Another object of the invention resides in the provision of means whereby the bends are formed in the metal bands in the forward cutting stroke of the knife.

Still another object of the invention is to provide a machine for the above purpose whereby the tipping of cords composed of a plurality of twisted strands is greatly facilitated thus admitting of a large number of the cord being provided with the tips in a minimum length of time and with a minimum of labor upon the part of the operator.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a side elevation of a cord tipping machine embodying the present invention; Fig. 2 is an enlarged vertical section of one end of the machine; Fig. 3 is

a transverse section taken on the line 3—3 of Fig. 2; Fig. 4 is a view similar to Fig. 2; showing the cutting knife at the end of its forward stroke; Fig. 5 is an inverted perspective view of the knife; Fig. 6 is a perspective view of the removable die block; Fig. 7 is a detail view of the operating means; Fig. 8 is a section taken on the line 8—8 of Fig. 7. Fig. 9 is a detail section taken on the line 9—9 of Fig. 2.

Referring in detail to the drawings, 5 designates two parallel longitudinal base bars which are provided with suitable attaching ears 6 whereby the same may be bolted or otherwise secured to a bench or other suitable support. These side bars are preferably formed of cast iron and are reduced in height at one of their ends as indicated at 7. The bars 5 are secured to the opposite longitudinal edges of a steel base bar 8 which is arranged between said bars, by means of a plurality of screws 9. The upper surface of this steel bar 8 is disposed below the plane of the upper edges of the reduced end portions 7 of the bars 5. The base bar 8 between the upwardly extending walls 10 of the side bars 5 is of increased thickness and is provided with a longitudinal groove 11.

Between the side walls 10 of the bars 5, a rod 12 is slidably mounted. To this rod, the knife 13 is attached in any preferred manner and rests upon the upper surface of the base bar 8. This knife at its forward end is provided with a transversely extending cutting edge indicated at 14. Upon the under surface of the knife 13, a vertically disposed longitudinally extending blade 15 is formed, having vertical cutting edge 16 at its forward end. This latter knife blade moves in the longitudinal groove or channel 11 in the upper surface of the bar 8.

Beyond one end of the groove 11 and in spaced relation thereto, a longitudinal arm or extension 17 is arranged between the reduced ends 7 of the side bars 5, and closely fits therein for adjustment toward and from the end of the groove or channel 11. Between the end of this extension 17 and the groove 11, a hardened steel die block 18 is adapted to be arranged between the side bars 5. This block is provided in its upper

surface with a longitudinal groove 19 which forms a continuation of the groove 11 and receives the additional knife blade 15 on the under side of the knife 13. A transverse groove 20 is also provided in the upper surface of the block 18 and intersects the longitudinal groove 19 intermediate of its ends. The purpose of this latter groove will be more fully disclosed in the following description. The arm or extension 17 and the block 18 are removably held in place by means of suitable set screws 18.

At the ends of the vertical walls 10 of the bars 5, and upon the reduced end portions 15 of said bars, the upright or vertical bar 21 is secured and is provided in its lower end with a central opening 22 for the passage of the knife 13. Upon one face of this vertical bar, a guide plate 23 is secured. Between this guide plate and the bar 21, a thin sheet or plate of steel 24 is secured. This steel sheet is interposed between a longitudinal guide channel 25 formed in the inner face of the plate 23 and the guide 25 grooves 26 formed in the opposed face of the vertical bar 21 through which the sheet metal bands 27 move. These bands are drawn from independently movable drums 28 mounted upon a suitable support 29 fixed 30 upon the upper end of the vertical bar 21. In the guide channel 25 of the plate 23, the vertically movable die 30 is mounted.

A frame is mounted upon the base of the machine, said frame including longitudinal bars 31 which may be integrally formed upon the upper ends of the standards 32 secured at their lower ends to the base of the machine. The forward ends of the longitudinal bars 31 of this frame are connected 40 to the vertical bar 21 and upon the bars 31, the supports 29 for the band reels are arranged. Between the longitudinal frame bars 31 a bell crank lever 33 is fulcrumed as indicated at 34. One arm of this lever extends forwardly and is disposed through 45 an opening provided in the upper end of the movable die 30. The other arm of this lever extends downwardly and is connected by means of a longitudinal bar 35 with the 50 depending arm of a bell crank lever 36 which is fulcrumed as indicated at 37 between the rear ends of the longitudinal frame bars 31. To the other arm of this bell crank lever the upper end of a connecting rod 38 is attached. The lower end of 55 this rod is connected to the crank 40 of a shaft 39 journaled in suitable bearings 41 mounted upon the upper edges of the longitudinal bars 50, of a suitable supporting 60 frame. Upon this shaft, a band or belt wheel 51 is loosely mounted and a collar 52 is keyed upon said shaft for sliding movement. This collar is provided with an arm 53 for engagement with one of a pair of

pins indicated at 54 which project from one 65 face of the belt wheel 51. A yoke 55 is fulcrumed as indicated at 56 upon one of the frame bars 50, the arms of said yoke being disposed upon opposite sides of the collar 52 and in an annular groove formed therein. 70 The lower end of this yoke has an angular extension 57 formed thereon, to the end of which the treadle bar 58 is fulcrumed as indicated at 59. The forward end of this treadle bar moves in a suitable guide 75 bracket 60. The rear end of this treadle bar is pivoted as shown at 61 upon the supporting frame. This treadle bar at its front end is yieldingly held against downward movement by means of a coil 80 spring 62.

To the lower end of the connecting rod or bar 38, one end of a coil spring 63 is attached, the other end of said spring being suitably secured to the supporting frame. 85 A longitudinally extending leaf spring 64 is also mounted in the frame and bears at its free end against the lower end of said connecting rod when the same is in its normal position. This spring intermediate of 90 its ends rests upon a lug or other suitable support 65 secured to the frame. The depending arm of the bell crank lever 36 is loosely disposed in an opening provided in the rear end of the knife carrying bar 12, 95 so that said bar and the movable die 30 will be simultaneously actuated, upon the movement of said lever.

Having now described the construction of the machine, its operation will be understood as follows: The operator takes his position in front of the machine and arranges upon the extension bar 17, a number of skeins of rope or twine to be tipped. It will be observed that the lower edge of the 100 sheet of steel 24 which is arranged between the guide plate 23 and the vertical bar 21, is disposed closely adjacent to the upper surface of the knife 13. The sheet metal bands 27 extend downwardly below the 105 edge of this steel sheet. Before the twine is placed in position in the transverse groove of the die block 18, the operator presses downwardly upon the forward end of the treadle bar 58, thereby shifting the 110 collar 52 upon the shaft 39 so that the arm 53 thereof will be engaged by one of the pins 54 on the belt wheel 51, thus rotating the shaft 39 and through the medium of the crank shaft and the connecting rod 38, oscillating the bell crank 36. The operator removes his foot from the treadle bar when the same has been forced downwardly and the coil spring 63 which has been placed under tension completes the revolution of the 115 shaft 39, the rotation of the shaft being stopped by the engagement of the lower end of the connecting rod with the end of the 120 125

leaf spring 64. During the latter half of the revolution of the shaft, the knife bar is being retracted. In the forward movement of the depending arm of the bell 5 crank lever 36, this knife bar is moved forwardly so that the knife 13 will engage the lower ends of the metal bands 27 and bend the same forwardly. In the reverse movement of the knife, the die 30 is moved down- 10 wardly upon the ends of the metal bands to force the same into the transverse groove of the die block 18, and thus produce loops thereon. The operator now places one of the circular lengths of twine or rope in 15 these loops or hooks on the lower ends of the bands 27 and again presses upon the treadle bar 58 so that the die 30 is moved upwardly and the knife 13 in its forward movement cuts the metal bands and bends 20 the same around the twine and simultaneously bends the lower ends of the bands remaining on the spool forwardly beneath the edge of the plate 24. After the loops have thus been clenched around the twine, the 25 vertical knife blade moving in the longitudinal groove of the die block 18, cuts the twine between the loops. The tipped ends of the cord or twine are then removed by the operator and the above described operation repeated. It will thus be seen that the 30 forwardly bent ends of the metal bands on the spools are simultaneously fed into the transverse groove of the die block and bent to produce the hooks thereon by the down- 35 ward movement of the die 30. The leaf spring 64 acts as a stop for the shaft 39 so that the same will make but one revolution upon each downward pressure of the operator's foot upon the treadle bar and the 40 release of said bar.

From the foregoing, it is believed that the construction, operation and many advantages of the machine will be clearly understood. It will be obvious that by means of 45 the same, the tipping of rope or twine such as is used in the construction of fly nets, in order to prevent the same unraveling, will be greatly expedited.

It will be obvious that if desired, the foot 50 treadle for the manual control of the machine may be eliminated and the machine operated from any suitable source of power. The stationary die block 18 may be readily removed from the bed of the machine and 55 another substituted therefor when cord or twine of various thicknesses is to be supplied with the metal tips. This is also true of the movable die member which forms the loops or hooks upon the ends of the metal bands, 60 as well as the double knife and the metal plate 24. It will further be understood that while I have shown and described the preferred construction and arrangement of the several parts, the invention is nevertheless,

susceptible of considerable modification in 65 the form, proportion and arrangement thereof without departing from the essential features or sacrificing any of the advantages thereof.

Having thus described the invention, what 70 is claimed is:

1. In a machine of the character described, a stationary die provided in its upper surface with a groove, a pair of plates arranged above said die, one of said plates being provided with spaced band receiving grooves and the opposed face of the other plate having a channel therein, a vertically movable die in said channel, a metal plate arranged between the band receiving grooves and the 75 die channel, said movable die being adapted to force the bands downwardly and into the groove in the stationary die and bend the same to receive a cord, and means for severing the bent cord receiving portions of 80 the bands and bending the projecting ends of said bands beneath the movable die and then subsequently severing the cord between the bands secured thereon.

2. In a machine of the character de- 90 scribed, a stationary die, a vertically movable die, a band guide, a slidably mounted knife movable beneath said band guide and over the stationary die, means for simultaneously actuating the movable die and said 95 knife to project the knife beneath the die when the same is raised and sever the metal bands and clench the same upon a cord arranged in the stationary die and an additional knife blade carried by the first named 100 knife to cut the cord between the clenched bands.

3. In a machine of the character de- 105 scribed, a stationary die provided in its upper surface with a groove, a vertically mov- 110 able die, a band guide provided with grooves to receive spaced metal bands, means for actuating the movable die to force the bands downwardly into the groove in the station- 115 ary die to form cord receiving loops thereon, and a slidably mounted duplex knife to sever the metal bands and bend the project- 120 ing ends thereof at right angles to the band guide and beneath the movable die and then subsequently cut the cord between the bands 125 clenched thereon.

4. In a machine of the character de- 125 scribed, a stationary die provided in its upper surface with intersecting grooves, a ver- 130 tically movable die, a band guide provided with grooves to receive spaced metal bands, said vertically movable die being adapted to engage the bands and force the same into one of the grooves of the stationary die and form cord receiving loops thereon, a slid- 135 ably mounted knife movable beneath the band guide to sever said bands and clench the same upon the cord, an additional cut-

ting knife formed upon the underside of
said first named knife and movable in the
other groove of the stationary die to cut the
cord between the bands, and means for ac-
tuating the movable die and said sliding
knife.

In testimony whereof I hereunto affix my
signature in the presence of two witnesses.

EDWARD W. ANDEREGG.
